Specification of Letters Patent. Patented Aug. 8, 1911.

Application filed July 7, 1910. Serial No. 570,695.

To all whom it may concern:

Be it known that I, GERALD W. HART, a citizen of the United States, residing at West Hartford, county of Hartford, State 5 of Connecticut, have invented certain new and useful Improvements in Switches, of which the following is a full, clear, and exact description.

My invention relates to remote controlled 10 switches and has for its object to provide a switch which shall be closed electrically and remain closed as long as the local circuit controller is closed, the switch being positively locked mechanically during such 15 period.

It further has for its object to provide a switch which is closed electrically and locked mechanically and in which the lock is released whenever the current ceases to flow 20 through the local circuit controller.

It further has for its object to provide a switch which has a closing coil and a locking coil and means controlled by the locking coil for cutting the closing coil out of 25 circuit when the switch is locked.

My invention is particularly adapted for use in connection with switches used on alternating current circuits, since with switches embodying my invention, the contact of the switch arm with the circuit terminals is not affected by the alternations 30 of the current, with the result that there is no vibration and consequent chattering at the points of engagement.

The following is a description of an embodiment of my invention, reference being had to the accompanying drawings, in which,

Figure 1 shows a plan view of a switch 40 embodying my invention; Fig. 2 is a side elevation of the same; Fig. 3 is a sectional view of the same on the line $x-x$ Fig. 1; Fig. 3^a shows certain parts of Fig. 3 in different relations; Figs. 4 and 5 are views of 45 details, and Fig. 6 is a diagram of circuits.

Referring more particularly to the drawings, 1 represents the switch base having main circuit terminals 2—2'.

3 is a switch arm secured to but insulated 50 from a support 4, which is adjustably connected to the core 5 by the screw-threaded post 6 which carries a set-nut 7.

To the base 1 are secured two cast frames 8—8' having two upright members as shown 55 in Fig. 2, connected by three horizontal

members 9—9'—9², as shown in Figs. 1 and 2. Between these cast frames is a fixed laminated magnetic core or yoke 10, Figs. 2 and 3, which is held between the frames 8—8' by insulated rivets passing through 60 said frames and the holes 11 of the laminated portion. This laminated core has two side members and three connecting members 12—12'—12² which coincide respectively with the portions 9—9'—9² of the 65 castings. Located a slight distance below the connecting portion 12' is a cast plate 13, suitably secured to the cast iron portions by screws 13'. This plate has a recess 14 adapted to partially receive two balls 15 70 for the purpose hereinafter described. Below the plate 13 is a coil 16 of a fairly low resistance but sufficiently high to carry current at the normal voltage of the circuit for a period somewhat longer than that necessary to close the switch. Above the cross-bar 12' is another coil made up of two sections 17—17'. It is made in two sections so that it may be placed in position although the laminated frame has a downward projection 18 constituting a partial 75 stationary core. The two sections 17—17' are introduced one at a time, section 17' being placed in position first, whereupon section 17 can be slipped in.

The portion 13 with its recess 14 for the balls 15 constitutes a stationary abutment. Within the coils 17—17' is a core 19 having laminations parallel to the laminations of the stationary core 10. Through this core 90 19 runs a non-magnetic rod 20, the lower end of which is secured to a movable abutment 21 having a recess 22, which, when the core 19 is in a depressed position, comes opposite the balls 15. The laminated portion of the core 19 bears against the top of the movable abutment and is held from upward movement on the rod 20 by a shoulder 20' from which it is separated by a fiber washer. To the upper end of the core 19 is connected 95 a square projection 23 having a round bore to receive the abutment 21 and also holes 24 through which the balls 15 may pass. This square projection 23 constitutes an intermediate member lying between the stationary 100 abutment 13 and the movable abutment 21. The wall of this intermediate member 23 should be slightly greater than one-half the diameter of the balls 15, and the recesses in the stationary and movable abutments 110

should be correspondingly less than half the diameter of said balls so that the hole in the intermediate member and a recess in one of the abutments will together have sufficient capacity to receive and contain a ball 15.

The upper part of the core 10 surrounding the coils 17-17' together with the core 19 are laminated when the switch is intended for alternating current circuits since these parts will be subjected to an alternating flux for extended periods and would otherwise have eddy currents generated therein. Lamination of the lower part of the core 10 and the core 5 is not so necessary since these parts are subjected to alternating magnetic flux for at most very brief periods. For this reason although I have shown the lower portion of the core 10 laminated I have not laminated the lower core.

On the upper flange 9² of the frame 8' I mount an auxiliary or supplemental circuit controller. This consists of a standard 25 carrying insulated contacts 26-26' which are adapted to be engaged by a bridging contact 27 carried by, but insulated from, a bell-crank 28 pivoted at 29 and having a rearward extension engaged by a spring 30 mounted in the standard 25. The free end of the bell-crank is thus held in mechanical connection with an adjustable button 31 screw-threaded upon the bar 20 and locked in position by a lock-nut 32, during the latter part of the upward movement of the core 19. When the bar 20 connected to the core 19 is raised to its highest position, the button 31 actuates the bell-crank 28 so as to separate the movable contact 27 from the stationary contacts 26-26' and thus interrupts a circuit through said stationary contacts.

33 is a fuse mounted on the casting 8' in series with the coils, 16, 17, 17', as shown in Fig. 6.

The diagram, Fig. 6, shows the preferred circuit connections for the switch. In this diagram, 50 and 51 are the mains of the circuit controlled by the switch. 52 are the translating devices. 53 is a local circuit controller, one contact of which is connected to the main 51. 33 is the fuse, to one terminal of which the other contact of the local circuit controller 53 is connected. To the other terminal of the fuse are connected two parallel circuits, one passing through the coils 17-17' to the main 50 and the other passing through the contacts 26, 27, 26' and the coil 16 to the main 50.

The operation of the apparatus is as follows: When the local circuit controller 53 is open the switch arm 3 is separated from the contacts 2-2' so as to open the switch as shown in the diagram, Fig. 6, and the contact member 27 is in engagement with the stationary contacts 26-26'. The mov-

able abutment will then be in its lowermost position, the balls being contained in the holes 24 and 22 so that the movable abutment 21 and intermediate member 23 are locked together. The balls, holes 24 and 22 will have also moved below the recess 14, as shown in Fig. 3^a. If now the local circuit controller 53 is closed, the circuit is completed through the coils 16, 17, 17'. The coil 16 is the most powerful coil and constitutes the switch-closing coil. It acts upon the core 5 to raise the switch arm so as to engage the contacts 2-2'. The coils 17-17' are simultaneously energized and act upon the core 19 to lift it. The lifting power of the coils 17-17' is, however, preferably such that they will do little more than lift the core 19 and hold it in supported position against the action of the spring 30, although incidentally they may assist the coil 16 somewhat in lifting the switch arm. The coil 17-17' must, however, have such a number of turns that on account of its resistance it will be able to withstand for an indefinite period the heating of such current as may pass through it. When the switch arm has been lifted into closed position, the intermediate member 23 connected to its core 5 will have been raised until the balls 15 carried thereby are opposite the recesses 14 in the stationary abutment 13. The balls contained in the holes 24 and recess 22 of the movable abutment 21 are then opposite the recesses 14 in the abutment 13. The movable abutment 21, on account of the action of the coils 17-17', tends to move still farther upward and in so moving forces the balls 15 through the holes 24 in the intermediate member 23 into the recesses 14 of the stationary abutment 13 and holds them locked in that position. The switch arm 3 is now mechanically locked in position and is held in that position irrespective of the condition of the lower coil 16. The latter part of the upward movement of the core 19 moves the bell-crank 28 against the resistance of its spring 30 so as to withdraw the movable contact 27 from the contacts 26 and 26', which are, in the embodiment shown, in the circuit containing the lower coil 16. This breaks the circuit through the lower coil, the circuit through the upper high resistance coil 17-17' being still maintained, and the current therethrough being sufficient to hold the armature 19 in elevated position maintains the switch arm locked to the stationary abutment 13. As long as the local circuit controller 53 is closed and normal potential is impressed upon the mains, the switch, when once closed, will remain closed, being mechanically locked. If, however, the switch 53 is open or the current fails in the coil 17-17' the core 19 will fall until its recess 22 comes opposite the balls 15, whereupon the tend-

ency of the switch arm and its core to move downward, will result in the movement of the balls 15 out of the recesses 14 into the recess 22, thus releasing the intermediate member 5 and permitting the switch arm to move to open position. The core 19 is carried downward by the movement of the switch arm, being at that time locked to the intermediate member on account of the engagement of the balls 15 with the movable abutment 21. The downward movement of the switch arm and the cores 5 and 9 is limited by the engagement of the nut 32 with the top of the laminated yoke 10. The switch arm is kept in alinement with the circuit terminals 2, 2', by reason of the fact that the core 5 is square and fits in a correspondingly shaped opening formed by the laminated portion 10 and the castings 8, 8'. The upper core 19 is also kept from turning by reason of its rectangular shape fitting in a corresponding hole so that its laminations are maintained parallel to the laminations of the stationary laminated portion 10. If the switch 53 remains closed during a period in which the current fails and then comes on again, the switch will be automatically opened and automatically closed again as soon as the current comes on and be relocked in its closed position. The mechanical locking of the switch arm makes a firm and positive contact, entirely independent of the alternations of the current when the circuit is an alternating current circuit. The fact that the lock is released and the switch is opened whenever the current fails permits the switch to be controlled from a distance by the mere opening and closing of the local circuit controller 53. The ball 40 detent with its hardened spherical surface enables it to withstand wear and act without seriously abrading co-acting surfaces. The invention permits of various modifications which will be evident to those skilled in the art, which modifications can be made without departing from the spirit thereof and will be within the scope of the appended claims.

What I claim is:

50. 1. In a switch, the combination of switch contacts, a switch arm adapted to engage therewith and normally tending to move away therefrom, a core connected to said arm, a solenoid acting on said core to move said arm into engagement with said contacts, a lock for holding said core in actuated position, a solenoid for actuating said lock, said solenoids being connected in shunt to the circuit controlled by said switch arm, and a manual local circuit controller in series with both of said solenoids.
2. In a switch, the combination of switch contacts, a switch arm adapted to engage therewith and normally tending to move away therefrom, a core connected to said
- 60
- 65

arm, a solenoid acting on said core to move said arm into engagement with said contacts, a lock for holding said core in actuated position, a second core controlling said lock, a solenoid for actuating said second core, said solenoids being connected in shunt to the circuit controlled by said switch arm, a local circuit controller for cutting out said first solenoid and controlled by said second core so as to be actuated thereby when the same is moved by its solenoid, and a manual local circuit controller in series with both of said solenoids.

3. In a switch, the combination of switch contacts, a switch arm adapted to engage therewith and normally tending to move away therefrom, a core connected to said arm, a solenoid acting on said core to move said arm into engagement with said contacts, a lock for holding said core in actuated position, a second core for controlling said lock, a solenoid for actuating said second core, local circuits for said solenoids connected in parallel, a circuit controller in the local circuit for said first solenoid controlled by said second core so as to be opened when said second core is actuated by its solenoid, and a manual circuit controller in series with both of said solenoids.

4. In a switch, the combination of switch contacts, a switch arm adapted to engage therewith and normally tending to move away therefrom, a core connected to said solenoid, a switch closing solenoid acting on said core, a lock, a core therefor in line with said first core, a solenoid for actuating said second core and in line with said first solenoid, two local circuits for said solenoids connected in parallel, a manual local circuit controller in series with both of said circuits and an auxiliary local circuit controller in the local circuit of said first solenoid and controlled by said second core so as to be opened thereby when said second solenoid is energized.

5. In a switch, the combination of switch contacts, a switch arm adapted to engage therewith and normally tending to move away therefrom, a core connected to said solenoid, a switch closing solenoid acting on said core, a lock, a laminated core therefor in line with said first core, a solenoid for actuating said second core and in line with said first solenoid, two local circuits for said solenoids connected in parallel, a manual local circuit controller in series with both of said circuits, an auxiliary local circuit controller in the local circuit of said first solenoid and controlled by said second core so as to be opened thereby when said second solenoid is energized and a laminated magnetic circuit for said second solenoid.

6. In a switch, the combination of switch contacts, a switch arm adapted to engage the same and normally tending to move

away therefrom, a core connected to said arm, a switch closing solenoid surrounding said core, a stationary abutment adjacent to said core, a movable abutment in proximity 5 to said stationary abutment, an intermediate member lying between said two abutments and connected to said core, a detent carried by said intermediate abutment, recesses in said movable and stationary abutments 10 adapted to partially receive said detent alternately, a core for controlling said movable abutment, a second solenoid surrounding said core, said solenoids being connected in shunt to the main circuit, a circuit controller for cutting out said first solenoid, and controlled by said second core so as to be opened when said second solenoid is energized to move said detent, and a manual circuit controller in series with both of said 15 local circuits.

7. In a switch, the combination of switch contacts, a switch arm adapted to engage the same and normally tending to move away therefrom, a core connected to said 25 arm, a switch closing solenoid surrounding said core, a stationary abutment adjacent to said core, a movable abutment in proximity to said stationary abutment, an intermediate member lying between said two abutments 30 and connected to said core, a detent carried by said intermediate abutment, recesses in said movable and stationary abutments adapted to partially receive said detent alternately, a core connected to said movable 35 abutment, a second solenoid surrounding said core, local circuits for said solenoids

connecting the same in parallel, a circuit controller in the circuit of said first solenoid, controlled by said second core so as to be opened when said second solenoid is energized to move said detent, and a manual circuit controller in series with both of said 40 local circuits.

8. In a switch, the combination of switch contacts, a movable switch arm adapted to engage therewith, a vertically movable member connected to said switch arm and having a passage therein, a second vertically movable member having a recess therein, a stationary abutment having a recess therein, 45 a detent in said passage in said first movable member adapted to extend through said passage and partially enter said recesses alternately, said movable members being adapted to move so as to bring both of said 50 recesses and said passage simultaneously in register, a solenoid acting on said first member for moving it so as to cause said switch arm to engage said contacts and to bring said passage and recesses simultaneously in 55 register, a second solenoid acting on said second member for moving it when said passage is in register with the recess in said stationary abutment so that the recess in said second member will move out of register 60 with said passage, and a manual circuit controller for said solenoid.
